UNITED STATES PATENT OFFICE.

DAVID W. OHAVER, OF ROCKVILLE, INDIANA, ASSIGNOR TO HENRY MANSFIELD, OF INDIANAPOLIS, INDIANA.

HAT AND COAT HANGER.

1,403,815.

Specification of Letters Patent. Patented Jan. 17, 1922.

Application filed May 18, 1921. Serial No. 470,507.

To all whom it may concern:

Be it known that I, DAVID W. OHAVER, a citizen of the United States, residing at Rockville, in the county of Parke and State 5 of Indiana, have invented certain new and useful Improvements in a Hat and Coat Hanger; and I do hereby declare the following to be a full, clear and exact description of the invention, such as will enable 10 others skilled in the art to which it appertains to make and use the same.

The object of the invention is to provide a simple and efficient hat and coat hanger adapted to be supported upon the back of a 15 chair or like object as for example the chairs or seats used in convention halls, churches, meeting houses and other places designed for the congregation of people desiring convenient means for supporting their out-door 20 wearing apparel, and moreover to provide a device for this purpose which can be attached firmly to the chair back without interfering with the occupation of the chair and without injury or damage to the surface 25 finish thereof and which will substantially support the articles suspended thereon; and with this object in view the invention consists in a construction, combination and relation of parts of which a preferred embodiment is shown in the drawing, wherein:

Figure 1 is a view of a hanger embodying the invention applied in the operative position to a chair.

Figure 2 is an edge view of the same.

Figure 3 is a front view.

The device consists essentially of the upper and lower substantially parallel bearing elements 10 and 11 which may be curved slightly to conform to the curvature transversely of the back 12 of a chair of ordinary construction, and a rack connecting said bearing element and consisting of the substantially parallel upright members 13 of which the upper ends are connected with the extremities of the upper bearing elements by means of upwardly directed loops 14 forming shoulders suitable for supporting a coat while the lower ends thereof are connected with the extremities of the lower bearing bar by means of loops 16 serving to space the body portion of the rack from the plane of the bearing bars to permit of the arrangement of the brim of a hat between the plane of the bearing bars and the 55 uprights as indicated by the dotted lines

in Fig. 2, the space between the upper end of the upright being open to permit of the insertion of the hat before the overcoat or other like article of wearing apparel is suspended from the shoulders formed by the 60 loops 14.

Near their lower ends as a means of reinforcement the uprights are connected by a transverse bar 17 constituting a rest which is preferably looped downwardly to form a 65 suitable seat for the crown of the hat arranged in the rack, and the upper bearing element is preferably formed in two separated sections connected by a looped saddle 19 constituting a hook for engagement over 70 the upper edge of the back of the chair to support the hanger thereon.

Also as a means of preventing the accidental disengagement of the hanger from the chair back, a retainer 20 may be employed consisting of an elastic band or spring 21 provided with terminal hooks 22 for engagement with the lower bearing element, said elastic band extending across the inner surface of a panel or chair back. 80

It will be obvious that the hanger may readily be applied to and removed from the back of a chair without marring or defacing the latter and when in place the only portions thereof which appear on the 85 front surface of the chair back are the looped portion of the saddle and the retainer, while a person occupying a chair in rear of that to which the hanger is applied may readily arrange his hat and overcoat 90 or like garment thereon to avoid the inconvenience of holding the same or having them drop to the floor.

Having thus described the invention, what I claim is:—

1. A hat and coat hanger for attachment to a chair back having a bearing element for contact with the chair back, and a rack consisting of upright members, loops connecting and spacing said element and members, and a rest bar connecting said members adjacent their lower ends. 95

2. A hat and coat hanger for attachment to a chair back having upper and lower bearing elements for contact with the chair 105 back and a rack consisting of upright members connected at their upper and lower extremities respectively with the said bearing elements and transversely connected near their lower ends by a rest bar, which is 110

centrally depressed to receive the crown of a hat.

3. A hat and coat hanger for attachment to a chair back having a bearing element for contact with the chair back and a rack consisting of upright members, and means connecting and spacing said elements and members including an upwardly directed loop.

10 4. A hat and coat hanger for attachment to a chair back having upper and lower bearing elements for contact with the chair back and a rack consisting of upright mem-

bers connected at their upper and lower extremities respectively with the said bearing elements and transversely connected near their lower ends by a rest bar, the lower extremities of the uprights being connected with the lower bearing member by means of lateral loops. 15 20

In testimony whereof I affix my signature in presence of two witnesses.

DAVID W. OHAVER.
